(57) **CLAIM**

The ornamental design for a gaming wheel, as shown and described.

DESCRIPTION

FIG. 1 is a front, left side perspective view of a gaming wheel, shown with environmental base in use, showing our new design;

FIG. 2 is a rear, right side perspective view thereof, shown with environmental base in use;

FIG. 3 is a rear, right side perspective view thereof;

FIG. 4 is a front elevation view thereof;

FIG. 5 is a rear elevation view thereof;

FIG. 6 is a top elevation view thereof;

FIG. 7 is a bottom elevation view thereof;

FIG. 8 is a left side elevation view thereof; and,

FIG. 9 is a right side elevation view thereof.

The broken lines shown in the drawings are included for the purpose of illustrating portions of the gaming wheel that form no part of the claimed design.

The broken lines on the base in FIGS. 1 and 2 are included for the purpose of illustrating environmental subject matter and form no part of the claimed design

The broken lines on portions of a steering wheel on FIGS. 1-3 of the gaming wheel illustrate unclaimed seams and form no part of the claimed design.

1 Claim, 7 Drawing Sheets
